CLAIM

The ornamental design for a putter head, as shown and described.

DESCRIPTION

FIG. 1 is a perspective view, showing portions of the top and right side of my new putter head design.

FIG. 2 is a perspective view, showing the bottom, and left side of my new design.

FIG. 3 is a side elevational view.

FIG. 4 is a front elevational view.

FIG. 5 is a bottom view.

FIG. 6 is a top view.

FIG. 7 is a rear view.

The broken line showing of a shaft portion is to indicate environment.
